CLAIM

The ornamental design for an ice chest cooler, as shown and described.

DESCRIPTION

FIG. 1 is a perspective view of the ice chest cooler with the door opened

FIG. 2 is a front view of the ice chest cooler with the door opened

FIG. 3 is a top view of the ice chest cooler with the door opened

FIG. 4 is a left view of the ice chest cooler with the door opened

FIG. 5 is a right view of the ice chest cooler with the door opened; and,

FIG. 6 is a front view of the ice chest cooler with the door opened and the front insulation piece closed.

The broken lines in the drawing represent portions of the ice chest cooler and form no part of the claimed design.
